VALÈRE A. FYNN, OF ST. LOUIS, MISSOURI, ASSIGNOR TO WAGNER ELECTRIC MANUFACTURING COMPANY, OF ST. LOUIS, MISSOURI, A CORPORATION OF MISSOURI.

IGNITION SYSTEM.

1,425,001.

Specification of Letters Patent. Patented Aug. 8, 1922.

Application filed March 7, 1918. Serial No. 221,065.

To all whom it may concern:

Be it known that I, VALÈRE A. FYNN, a subject of the King of England, residing at the city of St. Louis, State of Missouri, 5 United States of America, have invented a certain new and useful Ignition System, of which the following is such a full, clear, and exact description as will enable any one skilled in the art to which it appertains to 10 make and use the same, reference being had to the accompanying drawings, forming part of this specification.

My invention relates to an ignition system and more particularly to a battery ignition system operated in conjunction with a generator for charging said battery and operating in parallel with same.

It is known that battery ignition systems—particularly those in which the ignition circuit is normally closed—have the disadvantage of permitting useless drain on the battery, in case the ignition switch is left closed after the engine has come to rest and the timer happens to stop in its closed 20 position. In addition to this, it has been found that charging generators, particularly when used in connection with battery ignition systems installed on self-propelled vehicles, occasionally fail to excite, or "pick 25 up" as readily as desired. It is the object of my invention to overcome these defects. Other objects and advantages will appear from the following description and the appended drawings.

In carrying out my invention, I provide 30 an electromagnetic switch, for the primary ignition circuit, magnetize this switch by means connected permanently across the brushes of the charging dynamo, and also 40 provide additional magnetizing means for said switch. These additional means are used temporarily, generally during the starting operation, and only for the purpose of closing the switch. The first mentioned 45 means keeps the switch closed during normal operation.

In the accompanying drawings, Fig. 1 is 50 a diagrammatic representation of a battery charging and ignition system for automobiles and embodying my invention. Fig. 2 is a modification.

Referring to Fig. 1, the battery 2 is connected to the starting circuit including the starting switch 34 and the cranking motor 55 31 and to the lighting circuits 30, 32. The

charging generator has an armature 3 and a field winding 4. It is of the Sayers type and is provided with two main brushes, and an exciting brush displaced from the main brushes. The main exciting winding 4 is 60 connected between the exciting brush and one of the main brushes. The generator also carries an auxiliary exciting winding 5 which may be coaxially disposed with 4. A battery charging switch of usual construction, provided with an additional contact, is interposed between one terminal of the generator and one terminal of the battery. It comprises a core 15 provided with 65 a shunt exciting winding 8, connected to the main brushes of the generator, and a series magnetizing coil 9 adapted to be connected between one generator brush and one pole of the battery, when the battery switch is closed. The movable spring controlled element 10 of this switch is pivoted at 21 and carries two contacts 12 and 13 adapted to cooperate with the two stationary contacts 11 and 14. When this battery switch is 70 under the control of its spring, contact 12 rests on contact 11. When said switch is under the control of its core 15, then contacts 11 and 12 are separated and contacts 13 and 14 are in touch.

The spark coil 6 may be of the usual construction. One end of its high tension winding is shown grounded, while the other is connected to a distributor 33. The low tension winding of said coil is included in the primary ignition circuit which comprises the 85 timer 7, of ordinary construction, the usual hand-operated ignition switch 24 and the electromagnetic ignition switch 16, 23. The last mentioned switch comprises a core 16, provided with a magnetizing coil 18, permanently connected to the main brushes of the charging generator and a magnetizing coil 17, connected at one end to the auxiliary winding 5 of the generator and at the other to the spring controlled switch 28 90 through the electromagnet 29. The movable spring controlled element 23 of the electromagnetic switch is pivoted at 22 and carries a contact 20 adapted to cooperate 95 with the stationary contact 19.

In its normal position, the switch 28 rests on the contact 26 and completes the circuit between the battery 2, the auxiliary winding 5 of the generator and the magnetizing coil 17 of the electromagnetic switch, through the 100 105 110

resistance 27 and the hand-operated ignition switch 24. This switch 28 may, however, be moved to contact 25, in which case the circuit through the coils 5 and 17 will be completed through the stationary contact 11, the movable contact 12 and the spring controlled element 10 of the battery switch, as long as said switch is under the control of its spring, which is herein-
 5 referred to as its open position. The electromagnet 29 is so proportioned that it will hold switch 28 on point 25 as long as the battery switch remains open.

The operation of the battery switch is well
 10 understood. As soon as the speed of the internal combustion engine reaches a certain value, the voltage generated at the terminals of the charging dynamo, will be sufficient to produce in the core 15, by means of the coil
 15 8, a magnetization capable of overcoming the spring controlling the armature 10, with the result that this armature will be attracted and connection established between the contacts 13 and 14, while that between contacts
 20 11 and 12 will be broken. The connections to the coils 8 and 9 are so made that the magnetization they produce are of the same direction as long as the generator voltage is in excess of the battery voltage and
 25 current flows from the generator to the battery. When the generator voltage falls below that of the battery, as it will for instance do, when the engine speed diminishes below a certain value, then the battery will send a
 30 current into the generator, the magnetization produced by coil 9 will oppose that produced by coil 8 and the battery switch will open as soon as the difference between these two magnetizations has reached a sufficiently
 35 small value. The operation of the timer and of the distributor is well understood and need not be particularly described. The distributor, the cam of the timer, and the generator armature, are all driven from the engine.
 40 In operating the embodiment of this invention illustrated in Fig. 1, it is necessary to first close the hand-operated ignition switch 24. This will complete the circuit be-
 45 tween the battery 2, the auxiliary exciting winding 5 on the generator, and the magnetizing coil 17 on the ignition switch, through the holding electromagnet 29, switch 28, the contact 26 and the resistance 27. The
 50 resistance of this circuit and the number of turns on the coils 17 and 18 are so chosen that, with switch 28 on contact 26, the magnetization produced by coil 17 will not be sufficient to close or hold the electromagnetic switch, but the magnetization produced by the auxiliary exciting winding 5 will be ample to insure that the generator will "pick up" at the right speed. This auxiliary exci-
 55 tation taken from a source independent of the generator will also raise the terminal
 60 voltage of that machine when it is disconnected from the battery to values exceeding those which said voltage would have under the same conditions, but without this auxiliary excitation. With the engine at rest, 70 the battery switch will of course be open so that contacts 13 and 14 will be separated and contacts 11 and 12 will be in touch. The engine can now be started in any desired manner. It may, for instance, be set in motion 75 by means of a cranking motor 31, as is now usual. As soon as the circuit of the motor is closed, switch 28 should be moved from point 26 to point 25, thus cutting the resistance 27 out of circuit and raising the current 80 in the coil 17 to an extent sufficient to close the electromagnetic switch. As soon as the engine has fired, the starting switch 34 may be opened. When the engine runs fast enough to bring the charging generator 85 voltage to a value near that of the battery E. M. F. the battery switch will close, thus interrupting the circuit of the coils 5 and 17 at the points 11 and 12, and demagnetizing the electromagnet 29, which will yield switch 90 28 to the control of its spring. This switch will be carried back to point 26, but the electromagnetic switch will not open because the voltage of the generator is now amply sufficient to hold it closed by means of the mag- 95 netization produced by coil 18. Even if the battery switch is set to close at a speed exceeding the lowest operative speed of the engine, yet the electromagnetic switch will not open until the engine speed has fallen 100 below such speed, for coil 18 is so proportioned as to produce sufficient magnetization to hold this switch closed, with a generator voltage well below the battery voltage.
 The fact that the auxiliary exciting wind- 105 ing 5 of the charging generator is closed through the resistance 27 when the engine operates under its own power, also affects the output curve of said generator and 27 may be used, or not as desired. Omitting 110 this resistance 27—in other words, disconnecting point 26 from the negative pole of the battery—has the advantage of eliminating the useless small drain on the battery which would occur if switch 24 were left 115 closed after the engine has come to rest, but it will also reduce the generator voltage whenever the latter is disconnected from the battery. When the engine does come to rest, with the switch 28 on point 26, and whether 120 resistance 27 is used or not, the magnetization produced by the coil 18 necessarily falls to zero and the ignition circuit is opened at the electromagnetic switch, thus positively preventing a discharge of the battery 125 through the primary of the spark coil, in case the operator has forgotten to open the hand ignition switch 24.

If it is desired to interrupt the ignition while the engine is running, it is only neces- 130

sary to open the hand switch 24. In order to reinstate ignition under the same conditions, it is only necessary to close said switch, for as long as the engine revolves, coil 18 will 5 keep the electromagnetic switch closed. Should the generator fail, then it will be necessary to provisionally connect the point 26 with the negative pole of the battery. If a resistance 27 is used, then this connection 10 must be carried out by short-circuiting said resistance.

The modification shown in Fig. 2 differs from the arrangement illustrated in Fig. 1 in that the stationary contact 11, the connection 15 between it and the contact 25, the auxiliary contact 12 on the battery switch, and the holding electromagnet 29 are omitted, while point 25 is connected to the negative pole of the battery 2 through the hand 20 switch 24. In this figure, the coils 8 and 18 are connected in series instead of in parallel as in Figure 1. The operation of Fig. 2 is quite similar to that of Fig. 1. It is first necessary to close the hand ignition switch 25 24, then to crank the engine and hold the switch 28 on point 25 during the starting period, releasing same as soon as the engine has fired.

Having fully described my invention, 30 what I claim as new and desire to secure by Letters Patent of the United States is:

1. In a battery charging and ignition system, the combination of a self-excited generator, a battery, an ignition circuit, a controlling switch for said circuit, electromagnetic means permanently in circuit with the generator for holding said switch in closed position, means operated by the battery for closing said switch, and means in circuit 35 with the battery for producing an auxiliary magnetization in the generator to increase the range of generator speeds over which the said electric-magnetic means will hold the controlling switch closed.

40 2. In a battery charging and ignition system, the combination of a self-excited generator, a battery, an ignition circuit, an electromagnetic controlling switch therefor, said switch comprising two windings, one of said 45 windings being permanently connected in circuit with the generator, means for connecting the other winding in circuit with the battery, and means in circuit with the last mentioned means for producing an auxiliary magnetization in the generator.

50 3. In a battery charging and ignition system, a generator, a battery, a battery charg-

ing switch, an ignition circuit, a switch for controlling said circuit, and means governed by the battery charging switch for closing 60 the ignition controlling switch, said means being operative only when the battery charging switch is in open position.

4. In a battery charging and ignition system, a charging generator provided with 65 means for producing an auxiliary exciting magnetization, a battery, a switch for connecting the generator and battery, and means operable only when the battery switch is in open position to connect the battery to the 70 auxiliary magnetizing means.

5. In a battery charging and ignition system, a charging generator, a battery, an electromagnetically operated switch for connecting and disconnecting the battery from the 75 generator, an ignition circuit, an electromagnetically operated controlling switch for said circuit, means for supplying current to said switch to close the same, said means being controlled by the position of the battery 80 charging switch.

6. In a battery charging and ignition system, a charging generator provided with an auxiliary exciting winding, a battery, a battery charging switch for connecting and disconnecting the battery and generator, an ignition circuit, a controlling switch therefor, electromagnetic means for operating said switch, means for connecting the battery in circuit with said electromagnetic means and 85 with the generator exciting winding, said means comprising an electromagnetic switch adapted to complete said connection through a contact of the battery charging switch when said last named switch is open and 90 through a different path when said switch is closed.

7. In a battery charging and ignition system, the combination of a generator, a battery, a switch for connecting and disconnecting the battery and generator, an ignition circuit, a controlling switch therefor, an electromagnet for closing said switch, means for connecting said magnet in circuit with the battery, said means comprising contacts controlled by the battery switch, and a normally open switch, said last named switch being provided with means holding it closed while the battery is in circuit with the electromagnet operating the ignition controlling switch. 100 105 110

In testimony whereof, I have hereunto set my hand and affixed my seal.

VALÈRE A. FYNN. [L. s.]
